[57] CLAIM

The ornamental design for a combined plate and glass holder, as shown.

DESCRIPTION

FIG. 1 is a top perspective view of a combined plate and glass holder showing my new design;

FIG. 2 is a cross-sectional view thereof taken on line 2—2 of FIG. 1;

FIG. 3 is a bottom plan view thereof; and

FIG. 4 is a side elevational view thereof taken from the left of FIG. 1.
